UNITED STATES PATENT OFFICE

137,506

DESIGN FOR A COMBINED DIAL AND HAND FOR CLOCK OR SIMILAR ARTICLE

Frank A. Winders, Savannah, Ga.

Application June 28, 1943, Serial No. 110,547

Term of patent 14 years

(Cl. 42—10)

To all whom it may concern:

Be it known that I, Frank A. Winders, a citizen of the United States, residing at Savannah, in the county of Chatham and State of Georgia, have invented a new, original, and ornamental Design for a Combined Dial and Hand for Clock or Similar Article, of which the following is a specification, reference being had to the accompanying drawing, forming part thereof.

Figure 1 is a front elevational view of a com-

bined dial and hand for a clock or similar article, showing my new design; and

Figure 2 is a top plan view thereof.

The shaded and unshaded outer portions of the design indicate day and night.

I claim:

The ornamental design for a combined dial and hand for clock or similar article, substantially as shown and described.

FRANK A. WINDERS.
